UNITED STATES PATENT OFFICE.

JOHN THOMAS DANIEL, OF COLUMBIA, TENNESSEE.

LEVER-ACTUATED POWER-TRANSMISSION GEARING.

1,156,982.

Specification of Letters Patent.

Patented Oct. 19, 1915.

Application filed November 11, 1914. Serial No. 871,522.

To all whom it may concern:

Be it known that I, JOHN T. DANIEL, a citizen of the United States, residing at Columbia, in the county of Maury and State of Tennessee, have invented certain new and useful Improvements in Lever-Actuated Power-Transmission Gearing, of which the following is a specification, reference being had to the accompanying drawings.

10 This invention relates to an improved lever actuated power transmission gearing and has for its primary object to provide a simple and positively operating mechanism for transmitting power to the drive shaft of machines employed for various purposes.

The invention has for another of its objects to provide an improved combination and arrangement of the gear elements whereby power is transmitted to the driven shaft at a high speed upon the manipulation of a lever, one of said elements being so mounted that the same may be readily disposed in reversed position with respect to the gear on the driven shaft whereby said shaft may be driven in either direction at the will of the operator.

20 The invention has for a further and more specific object to provide a fulcrumed socket or housing for one end of the operating lever, and oppositely actuating dogs pivotally mounted in said housing to co-operate with the teeth of a ratchet wheel whereby power is transmitted through the gearing to the driven shaft.

25 My invention has for still another object to generally improve and simplify devices of the above character, increase their efficiency in operation and render the same capable of producing a high driving power at a minimum expenditure of manual labor.

With the above and other objects in view, my invention consists in certain novel constructions, combinations, and arrangements of parts to be hereinafter more fully described, claimed, and illustrated in the accompanying drawings, in which,

30 Figure 1 is a side elevation, partly in section, of the improved power transmission gearing embodying my invention in its preferred form; Fig. 2 is a section taken on the line 2—2 of Fig. 1; the top plate of the lever housing being removed; Fig. 3 is a section taken on the line 3—3 of Fig. 1; Fig. 4 is a fragmentary horizontal section taken 35 on the line 4—4 of Fig. 1; and Fig. 5 is a

longitudinal section taken on the line 5—5 of Fig. 2.

Referring in detail to the drawings, 5 indicates a suitable frame structure which includes a base 6. A socket member 7 is centrally secured in this base and projects above the upper surface thereof.

8 indicates a Babbitt metal bushing arranged in this socket member in which a journal stud 9 formed upon a ratchet wheel 10 is mounted. This ratchet wheel is rigidly fixed by means of suitable screws to the bottom face of an internal gear 11, the body of said gear being provided upon its outer edge with an upstanding flange formed with the inwardly projecting gear teeth indicated at 12. This internal gear 11 is centrally provided with an opening 13 to receive the lower end of the perpendicular shaft 14, said shaft, however, being spaced from the upper face of the ratchet wheel 10. This shaft 14 is centrally mounted in a horizontal bracing member 15 which is secured at its ends to the frame structure 5. Upon this brace or supporting member for the shaft 70 14, on opposite sides of said shaft, the depending stud bolts 16 are secured. Gears 17 are mounted upon said bolts for rotative movement between the body of the internal gear 11 and said member 15 and engage 75 with the teeth of a pinion 18 integrally formed with the shaft 14 at diametrically opposite points. The gears 17 mesh with the teeth 12 of the gear 11 and are positively driven thereby in the manner to be herein- 80 after explained.

A horizontally disposed top brace or supporting member for the shaft 14, indicated at 19, is clamped or otherwise secured at its ends to the frame 5. This upper frame 95 member is provided with an opening to receive the reduced upper end 20 of the shaft 14. This shaft is threaded, as at 21, for a short distance from the extension 20 thereon to receive a clamping nut 22. A plurality 100 of washers 23 are adapted to be arranged upon the shaft 14 between the nut 22 and a gear member 24 loosely arranged upon said shaft. This gear member rests upon an annular shoulder 25 formed upon the shaft 105 14 so that said member will not be frictionally engaged or clamped against the lower bracing member 15, but will be tightly secured upon the shaft 14 for rotation therewith. This member 24 is provided upon its 110

periphery with gear teeth 26, and is also formed with an annular series of teeth 27 upon its upper surface, said latter teeth being preferably tapered longitudinally, as shown, for engagement by a miter pinion 28 fixed upon the driven shaft 29. It is to be understood, however, that the invention is in no sense limited in this particular regard, as the teeth 27 can obviously be otherwise formed for engagement by various types of power transmission gears or pinions. The driven shaft 29, through the medium of which power is transmitted for the operation of a machine, is mounted in a suitable supporting bracket 31 arranged upon the frame 5.

A casing or housing 32 is fulcrumed upon a pin 33 fixed in the base 6 of the frame. The body of this casing is provided with a longitudinally extending socket 34 opening upon one end thereof, and upon the opposite walls of this socket, lugs 35 are formed.

36 designates the operating lever provided in opposite sides with recesses 37 to receive the lugs 35. In the end face of an enlargement 38 formed in the body of the housing or casing, a groove or channel 39 is formed to receive the dogs 40. These dogs are of a general longitudinally tapering form and have their smaller ends disposed respectively, in the opposite ends of the channel 39. The small ends of the dogs are provided with pivot lugs 41 for engagement in openings 42 formed in the body of the housing. These lugs also project above the upper face of said body and are adapted to be received in openings provided in a cap or cover plate 43 which is removably secured upon the body by means of suitable screws, indicated at 44. One of the dogs 40, at its outer end, is recessed or reduced in width to form an extension 45 thereon, while the other of said dogs is also notched or recessed to produce a lug or tooth 46 and a narrow longitudinal extension 47. These dogs 40, as clearly shown in Fig. 2 of the drawings, are inclined toward each other and are yieldingly held against the ratchet 10 by means of springs 48 mounted in the enlarged end of the body of the housing 32. These springs are connected at one of their ends to the respective dogs and one of said springs is connected at its other end to the plug 49 which is threaded in the body of the pivotally mounted lever housing 32. It will be readily understood, from this construction, that when the lever 36 is oscillated upon the pivot 33, the outer ends of the dogs 40 will alternately engage the teeth of the ratchet wheel 10 so as to impart a constant rotary movement thereto in one direction while a lever is manipulated. This ratchet wheel being fixed to the internal gear 11, will obviously also rotate said latter gear, and rotation will thus be transmitted through the inter-

mediate gears 17 mounted upon the brace member 15, to the perpendicular shaft 14 by the engagement of said gears with the pinions 18. The gear member 24 being fixed upon said shaft in the manner above pointed out, it will be seen that the shaft 29 is positively driven through the engagement of the pinion 28 thereon with the annular series of gear teeth 27 upon the upper face of said gear member. Any desired number of shafts may be geared to this member, or the driving force may be transmitted through the engagement of a gear with the peripheral teeth 26 upon said member 24. In order to reverse the direction of rotation of the driven shaft 29, it is only necessary to remove the nut 22 and the washers 23 on the shaft 14 and then remove the member 24 and replace the same in an inverted position, as illustrated in dotted lines in Fig. 1, or with the teeth 27 disposed above the pinion 28 and in engagement therewith.

From the foregoing description, taken in connection with the accompanying drawings, it is believed that the construction, manner of operation, and the several advantages of my invention will be clearly and fully understood.

The mechanism consists of a comparatively few elements which may be easily and quickly assembled or disassembled, and provides a highly durable and positively operating construction, whereby a machine operating shaft may be driven at a relatively high speed with comparatively little manual labor by the operator. It will of course be obvious that the ratios of the several gear elements may be varied, as desired, so as to rotate the driving shaft at a predetermined speed. It is also to be understood that while I have referred to a particular means for mounting the central perpendicular shaft of the several co-operating elements, this portion of the apparatus is susceptible of considerable modification. I therefore reserve the privilege of resorting to all such legitimate alterations in the form, proportions, and arrangement of the several parts as may be fairly embodied within the spirit and scope of the invention as claimed.

Having thus described the invention, what is claimed is:—

1. In a power transmission gearing, a driving shaft, a driven shaft, a reversible gear member on said driving shaft provided with an annular series of gear teeth upon one face, a pinion on the driven shaft, means for securing said gear member upon the driving shaft with its teeth in engagement with the teeth upon either side of said pinion to rotate the driven shaft in either direction, and means for rotating said driving shaft.

2. In a power transmission gearing, a driving shaft provided with an annular

shoulder, a driven shaft, a gear member arranged upon the driving shaft and provided with an annular series of teeth upon one face, a pinion upon the driven shaft to mesh with said teeth, a nut threaded upon one end of the driving shaft, a plurality of washers arranged between said nut and the gear member to clamp said member against the shoulder and with its teeth in engagement upon one side of the pinion of said driven shaft, said member being adapted to be removed and reversed upon the shaft and the spacing washers arranged between the same and the shoulder of said shaft, whereby the teeth of said member may be engaged upon the opposite side of said pinion and rotation of the driven shaft reversed, and means for rotating the driving shaft.

3. In a power transmission gearing, a vertically disposed driving shaft, a support therefor, a rotatable element, an internal gear fixed upon said element, gears mounted upon the support and meshing with said internal gear, a pinion on the shaft with which said latter gears are in mesh, a reversible gear member mounted upon the driving shaft, a driven shaft, a pinion fixed upon said driven shaft engaging said latter gear, means for securing said gear upon the vertical driving shaft for rotation therewith in engagement with either one of opposite sides of the pinion, whereby the rotation of the

driven shaft may be reversed, and manually operable means for positively operating said rotary element.

4. In a power transmission gearing, a driving shaft, a driven shaft, a reversible driving member removably mounted upon said driving shaft, a power transmission element on the driven shaft, a plurality of spacing collars upon the driving shaft to retain the driving member thereon in coöperative engagement in either of its positions with the element on the driven shaft, and means for rotating said driving shaft.

5. In a power transmission gearing, a driving shaft, a driven shaft, a reversible driving member removably mounted upon the driving shaft, a power transmission element fixed on the driven shaft, a plurality of collars removably mounted upon the driving shaft to retain the driving member thereon in either of its positions in coöperative engagement with said driven element, a nut threaded upon the driving shaft to clamp said driving member and the collars together for rotation with said shaft, and means for rotating said driving shaft.

In testimony whereof I hereunto affix my signature in the presence of two witnesses.

JOHN THOMAS DANIEL.
